(57) **CLAIM**

I claim the ornamental design for a bottle, as shown and described herein.

DESCRIPTION

FIG. 1 is a bottom, front, right side perspective view of a bottle showing my new design;

FIG. 2 is a top, front, left side perspective view of a bottle thereof;

FIG. 3 is a front elevation view thereof;

FIG. 4 is a right side elevation view thereof;

FIG. 5 is a left side elevation view thereof;

FIG. 6 is a rear elevation view thereof;

FIG. 7 is a top plan view thereof; and,

FIG. 8 is a bottom plan view thereof.

The dot-dash broken line(s) define the bounds of the claim and form no part thereof.

The dashed broken lines shown in the drawings are for illustrative purposes only and form no part of the claimed design.
